UNITED STATES PATENT OFFICE.

ATHERTON D. CONVERSE, OF WINCHENDON, MASSACHUSETTS.

COLLAPSIBLE SHOO-FLY ROCKER.

1,039,698.

Specification of Letters Patent.

Patented Oct. 1, 1912.

Application filed June 23, 1911. Serial No. 635,037.

To all whom it may concern:

Be it known that I, ATHERTON D. CONVERSE, a citizen of the United States of America, and a resident of Winchendon, in the county of Worcester and State of Massachusetts, have invented certain new and useful Improvements in Collapsible Shoo-Fly Rockers, of which the following is a specification.

10 This invention relates to collapsible rockers and particularly to that class of rockers which is known to the trade as "shoo-fly" rockers.

15 The object of the present invention is to provide a rocker which will be collapsible and occupy very little space in transit and in storage, and which may be readily put into operative condition when its use is desired.

20 The present invention is an improvement upon another application filed by John W. R. Andrews, May 18, 1911, Ser. No. 628,128.

25 The present invention consists in hinging to the body portion of each side member an extension which may be readily moved about the pivot of said hinges against the side faces of said body portion when it is desired to collapse the rocker for the purpose of shipping or while in storage.

30 The invention further consists in providing a play tray or other member interposed between said extensions which member is adapted to retain said extensions in the same plane with the body portion of the side members when the rocker is in use.

35 The invention further consists in certain novel features of construction and arrangement of parts which will be readily understood by reference to the description of the drawings and to the claims hereinafter given.

Of the drawings: Figure 1 represents a plan of a rocker embodying the features of the present invention. Fig. 2 represents a similar view, showing the rocker collapsed, and in condition for storage or shipping. Fig. 3 represents an elevation of the collapsed rocker. Fig. 4 represents a transverse section, the cutting plane being on line 4-4 on Fig. 1. Fig. 5 represents a similar section of the rocker when collapsed. Fig. 6 represents a perspective view of the play tray. Fig. 7 represents an enlarged detail showing the pivotal connection between the side frame and the extension

member hinged thereto, and Fig. 8 represents a similar view, showing the extension in the same plane with the side member, and retained in such position by means of the play tray.

Similar characters designate like parts throughout the several figures of the drawings.

In the drawings, 10 represents side frames which may be of any desired shape, as for instance, the shape of a horse or other animal, as indicated in Fig. 3 of the drawings. Each frame 10 is composed in part of a curved rocker member 11 adapted to rest on the floor and rock in the usual manner. Interposed between the side frames 10 is a folding seat 12 centrally divided at 13, the two parts of said seat being connected together by hinges 14 set into the under face of said seat so that the seat may be folded upwardly about the pivot of said hinges into the position shown in Figs. 2 and 5 of the drawings. The opposite edges of said seat are pivotally secured to the side frames 10 by means of hinges 15 set into the upper face of said seat 12 and the inner face of said side frames as clearly indicated in Fig. 2 of the drawings. The seat 12 is also provided with a back 18 centrally divided at 19, said back being wholly disconnected from the seat portion 12. The two parts of the back 18 are pivotally secured together by means of hinges 20 set into the front face of said back about the pivot of which said back is adapted to fold rearwardly into the position shown in Figs. 2 and 3 of the drawings. The opposite edges of the back 18 are pivotally secured by hinges 21 or other means to the side frames 10. Pivotally secured to the rear of one part of the back 18 is a latch member 22 adapted to engage a projection 23 secured to the rear face of the other part of said back, this latch 22 and projection 23 coacting to prevent the folding of the back when the rocker is in use.

It is obvious that when any weight, as for instance, that of a child, is resting upon the seat 12, the folding of said seat will be effectually prevented. When the rocker is desired for use it is in the condition shown in Figs. 1, 4, and 8 of the drawings, but when it is desired to ship the rocker or when it is desired to store it temporarily, the latch 22 is moved about its pivot to disengage from the hook projection 23, and the

back 18 is then permitted to fold rearwardly about the pivot of the hinges 20, into the position shown in Figs. 2, 3, and 5. At the same time the seat 12 is folded upwardly about the pivot of the hinges 14 into the position shown in Figs. 2, 3, and 5, thus permitting the side frames to be moved toward each other as shown in Figs. 2 and 5 of the drawings. To further reduce the space to be occupied by the rocker when in storage, or when ready for shipping, the body portion of the horse or animal has hinged thereto by means of hinges 24 any outwardly projecting extension such as the head portion 25 shown in Fig. 3 of the drawings. This head portion or extension may be moved about the pivot of the hinges 24 into contact with one face of the body portion of the side member 10, as indicated clearly in Figs. 2, 3, 5, and 7 of the drawings. This insures the rockers when packed occupying considerably less space, making it possible to pack them in cases of smaller dimensions, and obviating any danger of the heads or other extensions being broken in transit. Each head extension 25 has secured to its inner face a plurality of staples or other female members 26, which are adapted to receive the downwardly projecting male members 27 secured to a play tray 28 or some similar member. This tray or member 28 is interposed between the head extensions 25, and when the projections 27 are inserted into the staples 26, the extensions 25 are locked securely in position in the same plane with the body portion of the side members 10. To give increased rigidity to the rocker when in use, screws 29 may be inserted through the head extensions 25 into the ends of the play tray 28. When the head extensions 25 are moved about the pivot of the hinges 24 into contact with one face of the body portion of the side member 10 the staples 26 extend into recesses 30 formed in the face of said body portion. When in this position the rocker occupies but a little space, which is a great advantage in shipping, and results in a great saving to the wholesale and retail dealers where storage facilities are limited and rentals expensive. The device is of further advantage even after being sold, as in the home itself it is often desired to store the rockers temporarily and by folding the device as indicated in the drawings and described herein it may be placed in a closet or other limited compartment and occupy a very little space. Another advantage of the device is that all of the parts are permanently secured together, so that when the device is opened up for use no part can be missing and prevent its being placed in operative condition. Heretofore knock-down rockers have been used to reduce the cost of shipping and the expense of storage, but when it is necessary

to put the rocker on sale and exhibit the same, considerable work has to be performed to place it in operation, and oftentimes some of the disconnected parts are found to be missing, which makes the use of these knock-down rockers objectionable. In applicant's construction all of these objections have been fully overcome.

It is believed that the operation and many advantages of the invention will be 75 fully understood from the foregoing.

Having thus described my invention, I claim:

1. In a device of the class described, the combination of two side members; an extension hinged to each side member and adapted to be moved inwardly against the inner face thereof; a member adapted to be interposed between said extensions and means for locking said member to said extensions 85 to prevent the inward movement thereof.

2. In a device of the class described, the combination of two side members; an extension hinged to each side member and adapted to be moved inwardly against the inner 90 face thereof; a play tray adapted to be interposed between said extensions; and means for locking said tray to said extensions to prevent the inward movement thereof.

3. In a device of the class described, the combination of two side members; an extension hinged to each side member and movable into position against the inner face thereof; female members on the inner face of each extension; and a member provided 10 at each end with male members adapted to coact with said female members to lock said extensions in the same plane with said side members.

4. In a device of the class described, the combination of two side members; an extension hinged to each side member and movable into position against the inner face thereof; female members on the inner face of each extension; and a play tray provided 1 at each end with male members adapted to coact with said female members to lock said extensions in the same plane with said side members.

5. In a device of the class described, the combination of two side members; a collapsible seat interposed between said side members; an extension hinged to each side member and adapted to be moved inwardly against the inner face thereof; and a member adapted to be interposed between said extensions and locked thereto to prevent the inward movement thereof.

6. In a device of the class described, the combination of two side members; a collapsible seat interposed between said side members; an extension hinged to each side member and adapted to be moved inwardly against the inner face thereof; and a play tray adapted to be interposed between said

extensions and locked thereto to prevent the inward movement thereof.

7. In a device of the class described, the combination of two side members in the shape of the body of a horse; a collapsible seat interposed between said side members; a head hinged to each side member; and a play tray adapted to be interposed between and secured to said heads to lock them in 10 the same plane with said side members.

8. In a device of the class described, the combination of two side members; an extension hinged to each and adapted to be moved about said hinges against the face of 15 said side member; a member adapted to be interposed between said extensions; and means secured thereto to lock said exten-

sions in the same plane with said side members.

9. In a device of the class described, the combination of two side members; an extension hinged to each and adapted to be moved about said hinges against the face of 20 said side member; a play tray adapted to be interposed between said extensions; and means secured thereto to lock said extensions in the same plane with said side members. 25

Signed by me at Winchendon, Massachusetts this 1st day of June A. D. 1911.

ATHERTON D. CONVERSE.
